UNITED STATES PATENT OFFICE.

CHARLES R. SCHILLING, OF BELLEVUE, KENTUCKY.

WRAPPING-MACHINE.

SPECIFICATION forming part of Letters Patent No. 480,239, dated August 2, 1892.

Application filed March 1, 1890. Serial No. 342,237. (No model.)

To all whom it may concern:

Be it known that I, CHARLES R. SCHILLING, a citizen of the United States, residing at Bellevue, in the county of Campbell and State of Kentucky, have invented certain new and useful Improvements in Wrapping-Machines, of which the following is a specification.

My invention relates to improvements in machines for wrapping within paper or other similar suitable material articles of merchandise, such as soap, candy, and the like, the arrangement and construction of which will be fully hereinafter described, and particularly pointed out in the claims.

The machine herein described and shown is especially adapted for wrapping candy kisses and caramels.

In the accompanying drawings, Figure 1 is a longitudinal elevation of my machine; Fig. 2, a similar view of the same side of the machine, with some of the parts shown broken off or omitted to present a clear view of the internal mechanism; Fig. 3, a view similar to Fig. 2, but of the opposite side of the machine; Fig. 4, a front elevation; Fig. 5, a plan showing one end of the driving-shaft broken off; Fig. 6, a full-size section on line 1 1, Fig. 5, of one of the receptacles in the feed-disk for holding the article to be wrapped; Fig. 7, a broken sectional elevation of the lower portion of the frame of the machine, showing the discharge-table and discharge devices; Fig. 8, a broken sectional elevation on line 3 3, Fig. 7, of the devices shown therein; Fig. 9, a sectional plan on line 4 4 of Fig. 8; Fig. 10, a sectional elevation of the pedestal and box of the discharge device shown in Figs. 7 and 8; Fig. 11, a detail side elevation of the folder-carrier wheel or cylinder, showing one of the recesses or pockets on the periphery thereof in section and one of the yielding supports or rests for the article to be wrapped therein, together with the spring-jaws for holding said article in place; Fig. 12, a vertical cross-section on line 2 2, Fig. 11, of the cylinder shown in said figure with one of the tucker-carrier rings attached thereto; Fig. 13, a broken sectional elevation of one lower rear corner of the frame and base-plate, showing mounted thereon the upright cam-track for operating the end folders, the circular dotted line with arrow indicating the path of movement

of the periphery of the carrier-cylinder aforesaid; Fig. 14, a view, similar to Fig. 13, of the frame and discharge-table, showing mounted thereon the cam-track for operating the folders on the periphery or face of said carrier-cylinder; Fig. 15, a rear view of the parts shown in Fig. 14; Fig. 16, a broken longitudinal section of the operating-table, showing one of the feed-rolls mounted on adjustable or yielding-bearings therein, the dotted circle above said roll indicating the roughened feed-roll mounted on said table and the arrow indicating its direction of movement; Fig. 17, a detail elevation of two of the folder-fingers and connections, which are mounted on one side of said cylinder, and Fig. 18 the folder-fingers and a slotted link, which are mounted on the opposite side of said cylinder. Fig. 19 is a central vertical section of the cylinder B, the direction of the motion of which is represented by the arrow, the outlines of the track L being also shown. Fig. 20 is a central vertical transverse section of the cylinder, the tucker-carrying rings, and discharging mechanism. Fig. 21 is a perspective view of the paper wrapper before being applied to the article to be wrapped and after being cut by the knife H. Fig. 22 is a perspective view of the article before it has been wrapped. Figs. 23 to 29, inclusive, are perspective views of the several forms which the wrapper assumes. Fig. 30 is a detached end view of the cam K.

A represents a skeleton or open frame which supports the working parts of my machine, A' representing the horizontal feeding table or platen suitably mounted thereupon.

a, a represent two longitudinal connecting or brace bars, secured at their ends to the vertical pillars or legs of the frame A—one on either side of the frame about mid-height.

B represents a wheel or cylinder upon whose periphery the folding or wrapping devices are mounted. This wheel is mounted free to rotate upon a transverse rock-shaft b, which in turn is journaled at its ends in the said longitudinal brace-bars a a.

C represents a transverse shaft mounted in upright bearings c c on table A' and forming the main or principal actuating-shaft of the machine. In the several views of the drawings I have shown this main shaft provided with a handled crank C', by which it may be

- operated by hand; but in practice I prefer and intend using a pulley instead, which pulley is connected by belt with any suitable revolving power-transmitting shaft.
- 5 a' is a crank-arm secured to driving-shaft C and pivotally connecting, by means of a vertical pitman or rod a^2 , with the outer end of a rocker-arm a^3 , which latter is secured at its opposite end to the rock-shaft b. The said 10 pitman passes downward from said crank-arm a' through an opening a^4 in the table, as clearly shown in Fig. 5, and imparts intermittent motion to the wheel or cylinder B through the medium of a spring-controlled driving 15 pallet or pawl b' on the inner face of the rocker-arm a^3 , which pallet engages teeth b^2 on the periphery of a disk b^3 , constructed on the outer end of the hub b^4 of the main part or body of the said wheel or cylinder.
- 20 c' represents a vertical arm pivoted at its lower end on the longitudinal base-plate or discharge-table A² and having at its upper end an inwardly-projecting stud or stop-pin c^2 , which engages radial notches c^3 in said disk b^3 , and thereby firmly and steadily holds the wheel in position when the candy is feeding or the rock-shaft is moved backward in the upstrokes of the pitman.
- 25 c^4 is an actuating spiral spring strained between the vertical arm c' and the rear end of the discharge-plate A² to hold said arm and its stop-pin c^2 in working contact with the notched disk or ratchet-wheel b^3 , as shown in Fig. 3.
- 30 c^5 is a detent spring-pawl mounted on the inner face of vertical-arm c' and engaging the teeth b^2 to prevent backward motion of said wheel at any time, and particularly so when the stop-pin c^2 is thrown out of engagement with the ratchet-wheel b^3 for freeing the said wheel to move forward.
- 35 c^6 is a cam loosely mounted on the rock-shaft b intermediate the notched disk b^3 and the inner angular end of the rocker-arm a^3 and provided with stops or pins c^7 , which project from the rear end or hub thereof a suitable distance apart and lie in the path of the movement of the rocking arm at such a distance from its ends as to cause the rocking arm when finishing its upward stroke to strike the upper pin c^7 and to carry it a distance sufficient to cause the forwardly-projecting nose upon the cam to strike the upper end of the vertical arm c' and forcing it forward and releasing the ratchet-wheel b^3 from engagement with the stop-pin c^2 , the said nose holding the said arm c' forward until the rocker a^3 at the end of its downward stroke (in which it revolves the said ratchet-wheel) 45 strikes the lower pin c^7 , forcing the nose of the cam upward and permitting the arm c' to spring backward to its first position again, locking the ratchet-wheel by means of the stop-pin c^2 until it is again released by the 50 rocker-arm reaching the upward limits of its stroke.
- 40   D represents a horizontal carrier or feeding

disk mounted upon table a' at its forward end and turning on a short vertical shaft D'.

50   d are rectangular openings or pockets in a circular series or array, near the outer peripheral edge of disk D, and preferably provided with springs d' on each of their four walls hanging pendent and of just sufficient stiffness to properly support the candy in each 55 of the pockets after being placed therein by the operator and hold it in position for the operation of the feeding plunger or ram D² presently described.

60   Feed disk or carrier D revolves upon a metal-faced stationary circular bottom plate or track d^2 , located intermediate it and the face of table A', said springs d' in the candy-receiving pockets supporting said candy free from undue friction upon said plate. An 65 opening d^3 (see Fig. 2) is made in circular plate d^2 in line with the path of said ram D², through which the candy is fed to the wrapper immediately beneath.

70   d^4 is a projection or lip on the plate d^2 , under which the wrapping-strip of paper is fed beneath said ram, as hereinafter described.

75   D³ represents a longitudinal slotted bar adjacent one edge of the feed-disk and reciprocated along the upper face of table A' by 80 means of vertical crank-arm D⁴, which latter is secured at its lower end to the rock-shaft b and connected by a slotted rod or link D⁵ (at its upper end) with the slide-bar D³, as clearly shown in Fig. 1. Slide-bar D³ is provided with a pallet or click d^4 , which engages 85 peripheral notches d^5 in the feed-disk, and thereby imparts intermittent rotary motion to said disk to feed the candy up to said ram D².

90   D⁶ represents a hollow upright guide or race way, in which the ram or plunger D² reciprocates. This guideway extends upwardly from a base-plate d^6 , which spans a portion of the feed-disk and is suitably attached to the table A', with sufficient space between it and the upper face of said table to permit of both the presence and free rotation of said feed-disk. The upper end of ram D² is pivotally connected with an open concaved projection at one end of a rocker-arm or beam E, which latter pivots at or about its center upon an upright frame or support E' on the upper face of table A' intermediate the feed-disk and the main drive-shaft C. The rear end of the beam or rocker-arm E is provided with a 100 roller e, which projects laterally therefrom and is engaged by a cam E², keyed to said driving-shaft to make the downstroke of the ram. Said rear end of beam E is also provided with a spiral returning-spring E³, interposed between it and the table A' to automatically perform the upstroke of said ram. 105

110   F represents an ordinary roll of paper, in uniform strips or lengths of which the successive pieces or blocks of candy are wrapped. 115 This roll is mounted between two rearwardly-inclined bars f f, its shaft or axis bearing in notches at the lower ends of said bars, as clearly shown in Figs. 1, 2, and 3. Bars f f 120

are supported by a pair of hangers f' f'' from beneath the rear end of table A and are provided with a transverse roller f^2 , journaled in suitable bearings between their forward upper ends.

5 F' is a transverse roller journaled at its opposite ends in rocker-arms F^2 F^2 on table A in rear of a slot or opening F^3 , the latter being shown in Fig. 5.

10 F^4 is a transverse roller mounted in said opening F^3 , with its opposite axial ends bearing in boxes f^4 f^4 at both sides of said opening.

15 F^5 is a transverse roller mounted within an opening at the center of table A and journalled at its opposite ends in vertically-adjustable boxes f^5 , which are controlled or pressed upward by means of springs f^6 , as shown in Figs. 1 and 16.

20 F^6 is a bow or forked lever whose forward ends are pivotally connected to the axis or shaft of roller F^5 intermediate boxes f^5 and the ends of the roller, and which is provided with lateral pins or stops f^7 , upon which it pivots against the bottom of the table when 25 it is desired to lower said roller on its vertically sliding or adjustable bearings.

25 G is a roller keyed to a transverse shaft g in the upright frame E' (previously referred to) vertically above the roller F^5 . The face 30 of roller G is preferably roughened, as shown in Fig. 5, to provide a good frictional surface for the proper feeding of the strip of paper, the roller F^5 , through its springs f^6 , holding said paper up to said roughened roller 35 G with sufficient pressure for said feeding operation.

30 G' is a rocker crank-arm loosely mounted on the paper-feed roller G , and g' is a vertical link connecting the outer end of said crank-arm with the pitman a^2 for its actuation.

35 g^2 is a pallet or spring-click mounted on the inner face of crank-arm G' and engaging a toothed wheel or ratchet g^3 , keyed to shaft g for intermittently driving said shaft and its 40 paper-feeding roller at the desired time.

45 g^4 is an upright spring on the table A, forming a detent for the said ratchet g^3 .

50 H represents a transverse knife or shear reciprocating vertically in an upright frame h , mounted upon table A' intermediate the candy-carrier or feed-disk D and the paper-feeding roller G. At the opposite ends of knife H are suitable pins or gibbs which travel in slots or ways in the upright frame h , and 55 upon the backs of said upright, adjacent said slots, are spiral retractile springs h' , whose upper ends are attached to said uprights and connect at their lower ends with the pins which project through said slots, thereby providing means for returning said knife to its 60 upper normal position ready for another cut after each downward operating-stroke. The knife is operated by means of arm h^2 , which is pivoted intermediate its ends to the front 65 face of said upright directly above said knife, and is in turn operated by a vertical link h^3 ,

pivotally connected at its upper end with one end of a rocker-arm or beam h^4 , the latter being centrally pivoted to said frame E', and having at its opposite end a roller h^5 , which 70 is intermittently engaged by a cam H^5 , secured to the actuating-shaft C.

75 I represents a suitable printing wheel or drum mounted in upright bearings I' I' upon the rear end of table A' and provided with type-receptacles i on its face, and I^2 is an inking-roller of any desired construction journaled in the uprights I' I' , adjacent said printing-wheel, for applying the ink to the type set up in said receptacles. The printing-wheel 80 I is revolved at regular intervals by any suitable intermittent connection with the actuating-shaft C, the printing of the verse on the inner face of the paper taking place when the paper-feed rolls and the paper itself are at 85 rest.

85 I^3 is a spiral retractile spring strained between one of the rocker-arms F^2 and one of the uprights I' to properly hold roller F' and the paper running over it up to the type on 90 the printing wheel or drum I.

95 A gravitating weight or shoe I^4 is pivotally connected to the rear end of the bottom of table A' and spans the paper roll F, thereby exerting the proper pressure or tension thereon to prevent the paper paying out too rapidly or becoming too loose or slack in the feeding thereof.

100 The wheel or cylinder B, previously mentioned, has a series of deep peripheral notches 100 or recesses J, constructed at regular and suitable intervals apart to accommodate the successive blocks of candy or other material to be wrapped, as very clearly shown in the separate views of the wheel, Figs. 11, 12, 19, and 105 20.

110 J' represent U-shaped spring-jaws secured in recesses J, and J^2 are yielding supports or rests for the candy, mounted upon plungers or stems j , which slide in radial holes made in 115 the wheel and the central connecting portion of the spring-jaws J' , as shown in Figs. 11, 12, 19, and 20.

120 j' are horizontal pins or fingers projecting outwardly from the innermost ends of plungers j through radial slots j^2 in the wheel B, and j^3 is a cam secured to rock-shaft b, adjacent said wheel, with its nose or projecting portion disposed downwardly and in the circular path of said fingers j' , the backward or 125 reverse movement of said rock-shaft bringing said nose to bear against the lowermost pin j' to force its plunger j and candy-support J^2 outward in position for the last pass in the wrapping operation hereinafter described.

130 j^4 is a curved or bow spring attached at one end to the cam j^3 and disposed outwardly in a tangential line therefrom, and also in the path of the said plunger-pins j' , to exert a slight pressure on the pins and through them upon the plungers and candy-supports J^2 , thereby holding the candy in proper position in said

recesses J for the wrapping operation, and making due allowance for any ordinary irregularities in it.

J^5 is a strike pin or cam projecting radially from the hub of cam J^3 slightly in the rear of the nose of said cam and provided with an inclined or beveled outer end which is engaged by the said plunger-fingers J' and properly guides or forces them outward to the extreme end of their slots, thereby bringing the yielding supports or rests J^2 up to their normal positions and throwing open and holding their jaws J' apart for receiving the candy from the ram and feed-disk in the feeding operation.

K K represent a pair of cam-tracks or guideways attached to the hind legs of frame A and projecting inwardly therefrom (see Figs. 1, 3, 4, and 30) and has the forwardly-extending lips k^9 on its forward face, which serves as a guide for the rollers m^4 .

K' is an upright cam-track mounted upon the rear end of base-plate A^2 and having its face or operating edge constructed the greater part of its length in a curve concentric with the rock-shaft b , its upper end being inclined or beveled rearwardly and its lower end depressed or running slightly backward, as shown in detail in Fig. 13.

L is an upright curved arm or track, also concentric with said rock-shaft b and secured upon the rear end of said base-plate A^2 , adjacent said cam-track K' and in line with the center of the peripheral face of wheel B a suitable distance in rear thereof, for the purpose I shall presently describe.

l is a bifurcated presser-arm projecting from the upper end of the upright curved arm L and curved or bent downwardly and rearwardly in inverted-U shape, also hereinafter referred to in the description of the operation of the machine.

$L' L'$ are two rings, one of which is attached to each side of the wheel B by means of screws l' and spacing sleeves or tubes l^2 , as clearly shown in Figs. 4, 11, 12, and 20.

L^2 represents each one of a series of folder-plates on the periphery of wheel B. Each of these folder-plates is mounted at one end upon the cross-bar of a stirrup or U-shaped arm L^3 , whose arms span said wheel radially and are pivotally connected at their inner ends with both sides of said wheel, so as to move over the said jaws J' in the folding operation.

$l^3 l^3$ represent short lateral extensions or pins at the fore or free end of each of said folder-plates L^2 to engage the full width of the paper (more or less) in making the first fold in the wrapper.

L^5 is a flatplate-spring secured at its rear end to the fastened end of each of the folder-plates L^2 and exerting a suitable amount of pressure at its inwardly-bent portion on the said folder-plates to hold them down upon the first fold in the paper and the latter down upon the candy during the succeeding step

in the wrapping operation, which is that of making the other longitudinal fold in the paper.

L^4 represents each one of a series of folder-plates on the periphery of the wheel B, adjacent each of the recesses or jaws J on the peripheral side opposite to that occupied by each of the said folder-plates L^2 .

$l^4 l^4$ represent each pair of a series of radial bars or arms pivoted upon both sides of the wheel B and having at their outer ends the folder-plates L^4 , each one being pivotally mounted at its rear forked end therein and provided with a roller or trundle L^5 in said forked end, which rides upon the upright circular track or arm L, thereby operating one each of both said sets of folder-plates L^3 and L^4 simultaneously through the interposition of connecting rods or links l^5 , as shown in Figs. 3 and 19, the uppermost one of the folders L^2 being operated forward and making the first fold in the uppermost candy-wrapper while the folder L^4 , immediately preceding it, is being operated backward and making the second fold in the candy-wrapper ahead of said uppermost one. The connecting rods or links l^5 aforesaid are on one side of the wheel B only, and each one is pivotally attached at one of its ends to one of the inwardly-disposed arms of the stirrups L^3 intermediate the ends of said arm and at its other end is similarly attached to an inwardly-disposed extension, which is constructed on each of the radial arms l^4 on said side of the wheel only. A spiral or retractile spring l^6 is stretched between each of the connecting-links l^5 (at the end which is attached to stirrups L^3) and a pin or support l^7 on the inner face of the adjacent ring L' , as shown in Fig. 4, for automatically and immediately returning the several folders to their normal positions succeeding each movement thereof.

L^6 is a plate-spring attached to the forked ends of each of the folder-plates L^4 and disposed forwardly on the periphery of the wheel B, its free end bearing upon the face of said wheel, and thereby maintaining a suitable pressure on each of the said folders L^4 to hold it down upon the fold it has made in the wrapper until the succeeding step in the operation.

M represents each one of a series of folding fingers or tuckers mounted in circular series on both the rings $L' L'$, normally projecting in a radial line therefrom. These tuckers have cylindrical heads and are made L shape, being pivoted in the angle of the L to the inner ends of the radial portions of angular plates or supports M' , attached at suitable intervals apart on the periphery of both said rings.

M^2 represent each one of a series of bars or levers pivotally connected at its outer end upon the outer end of the radial part of one of said angular supports M' and having a notch m at its inner end in which plays an upright pin or screw m' on the inner end of

one of the said L-shaped tuckers, a small spiral or retractile spring m^2 being stretched between the top of said pin or screw m' and a screw m^3 on said lever M^2 to properly maintain said tucker in its normal position. Rollers m^4 , mounted on studs projecting outward at right angles to levers M^2 at their outer ends, ride upon or engage the said cams or guideways K K' , thereby operating the tuckers M both to and from the end fold in the paper wrapper, as hereinafter more fully mentioned.

N N' represent each pair of a series of folder-fingers on the cylinder B for making the fold on one side of both ends of the wrapper, and O O' are each pair of a series of similar folder-fingers for making the fold on the other side of both ends of said wrapper. Each pair of said folders N N' and O O' are firmly mounted upon a short shaft n and o , each of which passes transversely through the wheel B , adjacent one of the lower corners of the respective recesses J aforesaid, folder-fingers N and O being mounted at one end of each of said short shafts on one side of the wheel and folder-fingers N' and O' being at the other end of each of said shafts on the other side of said wheel. Folder-fingers N , N' , O , and O' are mounted intermediate their ends upon their shafts n and o , respectively, the inwardly-disposed ends of each set of fingers N' and O' , adjacent each recess J on one side of the wheel, being connected by a link N^2 , which prevents said fingers coming in contact, and one of them O' moving toward the said recess when the other N' is performing its operation on the wrapper, the slot N^3 in the end of said link, connecting with folder O' , being provided to permit the necessary play therein at the proper time.

On the opposite side of the wheel each of the fingers N is mounted at its inner end on one of the short shafts n and is pivotally connected with the inwardly-projecting end of the preceding finger O by means of a rod or link O^2 , so that a set of each of the folder-fingers N N' and O O' operate simultaneously, the former set (fingers N N') making the aforesaid fold on one side of both ends of one wrapper while the latter set (fingers O O') are making a similar fold on the other side of both ends of the wrapper ahead.

A spiral retractile spring P is stretched between each set of folder-fingers N N' and those ahead O O' on one side of the wheel by connecting its ends with the fingers N and O , as shown in Figs. 1, 2, 4, and 17, thereby sustaining said fingers in their normal positions and also automatically returning them to such normal positions after each operation on a wrapper. These springs P act as auxiliaries for the links N^2 to return said fingers to their normal positions, as stated. A roller n' is mounted on a stud projecting laterally from the outer end of each folder-finger N and engages the cam-track K' aforesaid to cause the

operation of the folder-fingers in the rotation of folder-carrier wheel B .

Q represents a vertically - movable flat-headed pedestal at the middle of the discharge-table A^2 in a perpendicular line with the feeding-ram D^2 and the uppermost and lowermost candy-recesses J of the folder-carrier wheel for receiving and supporting the wrapped candy during the last pass in the wrapping operation. This headed pedestal or stem passes downward through a central opening in the discharge-table and the bore of a box R , the latter having a circular upper end or shank r , which fits in an enlargement 80 or block r' on the bottom of the said discharge-table below its said central opening and is detachably secured therein by a screw r^2 , as clearly shown in Figs. 7, 8, 10, and 20. The lower portion of the stem of pedestal Q is of 85 less diameter than the upper and is provided within box R with an encircling spiral spring R' , the expansive pressure of which properly supports the pedestal and at the same time permits it to yield the proper distance when 90 a downward pressure is brought to bear on its head, as hereinafter described.

R^2 is a rectangular sleeve or sliding box surrounding the box R and provided with two vertical arms R^3 R^4 , whose lower ends are 95 pivoted in bearings r^3 at the lower ends of both sides thereof, as clearly shown in Figs. 7, 8, and 20. Said arms R^3 project through transverse slots R^4 in the discharge-table A^2 , and have shouldered jaws R^5 at their upper 100 ends which make the last pass in the wrapping operation and also grasp the wrapped candy, holding it on the yielding or spring-supported pedestal until finally ejected or discharged through the large opening R^6 in 105 said discharge-table.

r^4 is a pendent plate-spring secured at its upper end to the upper end of box R and exerting its pressure at its lower end on the transversely-channeled face r^5 of said sliding 110 box R^2 , thereby serving as a temporary frictional device for maintaining the jaw-arms R^3 in either their closed or open position in relation to the wrapped candy at the close of the wrapping operation.

S represent two knee-shaped arms projecting from a transverse rock-shaft S' beneath said discharge-table, said rock-shaft being journaled in bearings at the fore end of said discharge-table and having at one of its ends 115 120 (which projects a suitable distance beyond the discharge-table) an upright lever or arm S^2 , connecting by a horizontal rod or link S^3 with the pitman a^2 for its actuation.

s represents a transverse bar connecting 125 the free ends of arms S S' , thus practically forming an actuating-stirrup for the discharge mechanism.

S' S' are inwardly-disposed plates secured upon the inner faces of said free ends of arms 130 S S' and provided with inclined cam-slots s^2 s^3 , into which project pins s^3 s^3 on the upright

jaw-arms R^3 R^3 for performing the functions of closing said jaws R^3 and throwing them apart, and also reciprocating the sliding box R^2 on the box R .

5 T represents a pair of upright arms connected by a cross-bar T' , the latter being secured centrally upon the lower end of the pedestal-stem Q , as shown in Figs. 4, 7, 8, and 20. These arms embrace both sides of the box R and slide freely up and down thereon in the operation of the device, in contact with the bottom of sliding box R^2 , their principal object being to prevent the turning of said pedestal in its guideway or bearing at any time, 10 thus especially obviating any improper accidental shifting of the wrapped candy in the closing step of the wrapping operation. An upright pin t upon the top of one of the arms T and sliding in a hole in one of the bearing-boxes r^3 , as shown in Fig. 7, may be provided as an extra precaution to prevent the turning of said pedestal for the object above mentioned.

The operation of the machine is as follows: 15 Fig. 2 illustrates the various parts in the respective positions they assume immediately after the ram D^2 has fed or delivered a block of candy or what is commonly called a "sugar-kiss" or a "caramel," with its open wrapper, 20 into the uppermost recess or jaw T of the cylinder B , lowering or depressing the yielding supports or rests J^2 ahead of it. The longitudinal portions of said wrapper are shown standing upright from said jaw in the said view. (Also shown in Fig. 23.) Motion being 25 imparted to driving-shaft C in the direction of the arrow, the downstroke of the pitman a^2 actuates the rocker-arm a^3 , which in turn actuates rock-shaft b , carrying the cylinder B a sufficient distance to bring the next jaw or 30 recess J in said cylinder under the guideway of the ram. During the said limited movement of the cylinder B and downstroke of the pitman the following movements of certain 35 parts of the machine take place: Immediately upon the starting of cylinder B the roller L^5 , adjacent the jaw J , which is just ahead of said uppermost jaw, engages the cam-track L and, through the medium of one 40 of the extension radial arms l^4 and connecting-rods l^5 , simultaneously brings the peripheral folder-plate L^2 , lying back (to the right) of the upwardly-projecting portion of said uppermost wrapper, forward over the candy, 45 thereby making the first fold in the said uppermost wrapper, Fig. 24. At the time said roller L^5 starts to engage the said cam-track L it causes its adjoining folder L^4 to move 50 backward over its adjoining jaw, thereby 55 making the second fold, Fig. 25, in the wrapper of the candy just ahead of said uppermost one simultaneous with the making of said first fold in the latter. Simultaneous 60 with the initial engagement of said roller L^5 65 with the upper end of cam-track L the curved or rounded free ends of the bifurcated arm l are engaged by the radially-projecting por-

tions of the wrapper, afterward constituting the second fold therein, thereby laying the said portion of the wrapper in position, 70 ready for the next engagement therewith of the folder L^4 . The arm l is bifurcated or forked, as shown and hereinbefore described, for two purposes—viz., that of presenting a broad guide for the full width (more or less) 75 of said second fold in the wrapper, and also providing an opening through which the projecting rollers L^5 on the cylinder B may pass without obstruction. Simultaneous, also, with said initial contact of said roller L^5 80 with the cam-track L the roller L^5 just ahead of it has reached the end of its stroke at the lower end of said cam-track, one of the springs t , which has been expanded or stretched by said stroke of the last-mentioned 85 roller L^5 , now withdraws or retracts the folder L^4 from the second fold in the candy-wrapper adjacent said last-mentioned roller L^5 , and also the folder L^2 , from the first fold in the candy-wrapper adjacent the immediately-suc- 90 ceeding roller L^5 at the top of said cam-track. Immediately after the folder L^4 has made the second fold in the wrapper at the start of of the engagement of its adjacent roller L^5 with cam-track L a pair of the tuckers M on 95 the rings $L' L'$ at both sides of the cylinder are brought into engagement with the upper opposite ends of the now longitudinally-folded wrapper, thereby laying said upper ends down upon the ends of the candy, Fig. 26, ready 100 for the side laps or folds of said opposite ends. This movement of the tuckers M is caused by the rollers m^4 , mounted on their actuating-levers M^2 , engaging the cams or guideways K K , their return movement to normal position 105 being caused by continuations of said guide-ways and the small spirals m^2 . At or about the time the tuckers M have performed their function and at or about the middle of said downstroke of the pitman the vertical jaw-arms R^3 are thrown open on their respective 110 axes through the instrumentality of the knee-shaped arms or levers $S S$, whose rock-shaft S' is so turned by the upright arm S^2 and rod or link S^3 , the latter connecting upright arm 115 S^2 with said pitman as to rock said levers S upward a portion of their full stroke only, thereby also permitting the spring-controlled pedestal Q to rise very slightly. The jaws R^5 at the upper ends of said arms R^3 being 120 spread apart at this moment and the pedestal Q supporting the wrapped candy in the open- 125 ing between them, the next succeeding roller L^5 on the periphery of the moving cylinder B passes unobstructed through said opening be- 130 tween said jaws and ejects or throws said wrapped candy from the pedestal Q , which candy escapes through the opening R^6 in the discharge-table into any suitable receptacle beneath. Simultaneous with said movement of the roller L^5 in ejecting the candy from pedestal Q motion is imparted to the notched feed-disk D by the slide-bar D^3 and its pallet d^4 , they in turn being operated by the link

D⁵, crank-arm D⁴, and the wheel rock-shaft b, as hereinbefore explained. Said motion is of sufficient length to bring into the downward path of the ram D² the candy-filled pocket d, 5 lying next to the empty one previously under said ram and which held the candy in the said uppermost jaw J on the wheel. The motion necessary to complete the distance between the pockets d in said feed-disk and carry 10 each successive candy up to the ram is sufficient to bring the pitman to the end of its downward stroke, and simultaneous with that motion the jaw-arms R³ are raised, spread wide open as high as they will go in their upward movement, together with pedestal Q, 15 ready for the last pass in wrapping the next piece of candy. Simultaneous with the entire downward stroke of said pitman the roughened roll is revolved for feeding the strip of 20 paper under the lipped projection d³ on the feed-disk, bottom plate, or track d², ready for the next candy in the feed-disk. Motion is imparted to said roughened paper-feed roller G by means of rocker crank-arm G', loosely 25 mounted on its shaft g, and the vertical link g', connecting said crank-arm G' with the pitman for its actuation. Said rocker-arm G' is intermittently coupled with the roller-shaft g by means of the pallet g² engaging 30 the ratchet or toothed wheel g³, keyed to said roller-shaft, thereby communicating similar intermittent motion to said shaft and its paper-feed roller. In the intermittent forward movement of the cylinder B and the 35 said downstroke of the pitman the pins j', projecting from the inner ends of plungers J² j on one side of said cylinder, assume the positions shown in Fig. 2. At or about the middle of said downstroke of the pitman a set of 40 each of the end folder-fingers N N' and O O' operates simultaneously on the two candy-wrappers just ahead of said uppermost one. In their operation roller n' on the folder-finger N, now adjacent the upper end of the cam- 45 track K', engages the upper inclined end of said cam-track K' immediately following the completion of the full stroke of the tucker-fingers M, above described. At the time said roller n' begins to engage said cam-track it 50 simultaneously brings into operation its adjacent set of fingers N and N' and the set of fingers O O', adjacent the jaw or recess J immediately preceding, and holds said fingers in contact with the folds they make in the 55 ends of both wrappers (see Figs. 27 and 28, respectively) until it reaches the depression at the lower end of said cam-track when it is released, at which time both said sets of fingers return to their normal positions through 60 the reaction of their spiral connecting-spring P, the slotted link N² bringing the set of folders O and O' to said normal positions at said time. At the termination of the downstroke of the pitman, when the paper has been fed 65 the proper length for a wrapper, the shear H immediately begins to descend and, during the initial upstroke of the pitman, completes its work of cutting said length through the medium of the arm h², vertical link h³, and rocker-beam h⁴, the latter having roller h⁵, 70 which is intermittently engaged by cam H' on the actuating-shaft C for said cutting operation. The shear is automatically returned to its normal position immediately after cutting said paper by means of the retractile 75 springs h', as hereinbefore fully described. At or about the middle of the upstroke of the pitman the jaws R⁵ at the upper ends of arms R³ close on the upturned folded and pointed ends of the lowermost wrapper, their shoul- 80 dered portions engaging said upturned ends or points and laying them down over the corners on the back of said wrapper, Fig. 29. The said arms R³, with the wrapped candy embraced between their shouldered jaws R⁵ 85 and the head of pedestal Q, now descend with said pedestal and assume position for the proper ejection of said wrapped candy, as hereinbefore described. During the latter half of the upstroke of the pitman the slide- 90 bar D³ and its pallet d⁴ return to their normal positions with said pallet in engagement with the next tooth of the feed-disk D, ready for carrying the candy (immediately following that now under the ram) forward 95 under said ram for the wrapping operation. The downstroke of said ram takes place during the said latter half of the upstroke of the pitman, driving or delivering the candy lying in the pocket of the feed-disk into the now 100 uppermost recess of the cylinder. The reaction of spiral spring E³ returns said ram to its normal position at the upper end of its raceway D⁶ at the time the pitman is about to begin its downstroke and when the cam E² 105 has just passed or released the roller e on its operating-beam E. The passage or direction of the paper in feeding to the ram-opening above the cylinder is clearly shown in Fig. 2 and needs no detailed description herein other 110 than that given in connection with its guide or supporting rollers, hereinbefore fully described. In said Fig. 2 the end of the paper is shown under the lipped tongue d³ of the feed-disk track d² ready for the next cut of 115 the shear. 120

The purposes and operations of the other detail parts are fully hereinbefore described and will need no further detailed reference here.

I claim—

1. In a wrapping-machine, the combination of a revolving folder-carrying wheel or cylinder mounted upon a shaft within a suitable frame, a feeding-table above said cylinder, a revolving feed-disk and ram on said table, a paper-feeding mechanism on said table, a discharge or base plate below said cylinder, a receiving or holding pedestal and arms or jaws on said base-plate, and suitable cam and 125 crank driving mechanism for actuating said parts, constructed, arranged, and adapted to operate substantially as herein set forth.
2. In a wrapping-machine, a revolving

wheel or cylinder B, mounted on a rock-shaft, carried by a suitable frame and having radial recesses J in its periphery at suitable intervals apart, spring-jaws J', forming the opposite end walls of said recesses, yielding plungers J², forming the bottoms of the jaws for receiving and supporting the respective articles to be wrapped and their wrappers, pins or fingers j', projecting from the innermost ends of said plungers J² j through radial slots in said wheel, cam j³ on said wheel-shaft, curved or bow spring j⁴ on said cam, and strike-pin j, also on said cam in rear of its projecting portion, and mechanism for intermittently revolving said wheel on said shaft, substantially as herein set forth.

3. In a wrapping-machine, the combination, with a revolving wheel or cylinder B, in whose periphery are constructed recesses J, having

yielding holder-jaws which are self-conforming to ordinary irregularities in the articles to be wrapped, and means for operating the yielding bottoms of said self-conforming jaws, of peripheral folder-plates L² and L⁴, side folder-fingers N N' and O O', rings L' L' on the opposite sides of said wheel, folding fingers or tuckers M on said rings in line with said recesses or jaws J, projecting rollers L⁵ on said folders, and cam-tracks K K K' L, said folder-fingers, and also the tuckers, being suitably mounted on the wheel and rings, respectively, and all the parts being arranged, connected, and adapted to operate substantially as herein set forth.

CHARLES R. SCHILLING.
